CLAIM

I claim the ornamental design for a light, as shown and described.

DESCRIPTION

FIG. 1 is a perspective view of the top, front and left side of the professional light showing my new design;

FIG. 2 is an elevation view of the left side thereof, the right side being a mirror image;

FIG. 3 is a plan view of the top thereof;

FIG. 4 is an elevation view of the front thereof;

FIG. 5 is an elevation view of the back thereof; and,

FIG. 6 is a plan view of the bottom thereof.

The broken line showing represents portions of the article not claimed and forms no part of the claimed design.
